FORCED CIRCULATION AIR HEATER

Don F. Jones, John W. Miller, and Basil D. Figg,
Lansing, Mich., assignors to Motor Wheel Corporation,
Lansing, Mich., a corporation of Michigan

Application March 15, 1946, Serial No. 654,710

3 Claims. (Cl. 126—110)

1

This invention relates to heaters and more particularly to heaters adapted to receive and discharge air through one side only, such as heaters adapted to be mounted within a wall.

The principal object of the invention is to provide a wall type heater which is thoroughly insulated in a novel manner on those sides which are located close to the wall.

Another object is to provide a heater of the type mentioned which is particularly efficient, yet is economical to fabricate and install.

A still further object is to provide a heater which is adapted to circulate air by gravity and by means of a fan so as to distribute heated air substantially uniformly throughout the room in which the heater is installed.

These objects will more fully appear in the following specification when read in connection with the accompanying drawings, wherein:

Figure 1 is a front elevational view of a wall type heater embodying the invention;

Figure 2 is a side elevational view of the same;

Figure 3 is a plan view of the heater;

Figure 4 is a cross-sectional view taken on substantially the line 4—4 of Figure 3; and

Figure 5 is a cross-sectional view taken on substantially the line 5—5 of Figure 3.

The heater shown in the drawings comprises an outer casing 10 having a heat exchanger 11 therein. The outer casing is adapted to be set into a wall 13 of a building, as indicated in Figure 2.

The outer casing comprises a floor plate 14 of sheet metal having an upturned peripheral flange 15 to which a pair of side walls 16 and 17, a back wall 18, and a front wall 19 are attached. The floor plate has an opening 20 therein, the purpose of which will appear later. The walls are all fashioned from sheet metal. The side walls 16 and 17 are formed to the configuration shown in Figure 2, that is, the front, the bottom and a portion of the back edges are straight, while the rest of the back edge is of arcuate shape. The back wall 18 is attached to the floor plate and to the rear edges of the side walls and conforms thereto. The back wall is also attached to the front wall by a flange 21 at its upper edge.

The front wall 19 is provided with two large rectangular openings therein which are closed by swinging doors 22 and 23 to provide access to the interior of the casing. Louvers 24 are formed in the front wall above door 2. Other louvers 25 and 26 are formed in the wall 19 below the door 22. In the door 23, adjacent its upper and lower ends, are louvers 27 and 28. A grille 29 is at-

2

tached to door 23 over a rectangular opening therein.

The heat exchanger 11 may be of any conventional type, but preferably it comprises a sheet metal shell 30, in the lower part of which is mounted a vaporizing burner 31. The upper end of the heat exchanger is provided with a flue outlet 32.

The heat exchanger is mounted at one side of the center of the outer casing 10, as shown in Figure 4, on a sheet metal base 33. The base has a top wall on which the burner 31 and shell 30 are mounted. The base also is provided with a depending perimetral flange 34. Relatively large rectangular openings 35, 36, 37 and 38 are cut in the flange 34 on all four sides of the base. In the top of the base is an opening 33a to admit air to the burner. The back and two sides of the base are spaced from the respective walls of the casing, while the front of the base is in contact with the front wall. The opening 38 is in registry with the two bottom louvers 26 in the front wall.

The back wall 18 and the two side walls 16 and 17 are insulated from the heat exchanger by means of baffles 39, 40 and 41, respectively. The baffle 39 is substantially coextensive in area with the back wall, and extends upwardly from the base to a point adjacent, but spaced from, the front wall 19. The baffle 39 follows the curved contour of the back wall and is spaced from the back wall. The lower end of the baffle 39 is provided with an opening registering with the opening 35 in the base.

The baffle 41 extends from the base 33 to a point above the heat exchanger, and from the front wall to the baffle 39. The baffle 41 is located, throughout the greater portion of its area, in spaced parallel relation to the side wall 17. The lower end of baffle 41 has an opening registering with opening 37 in the base.

The baffle 40 is in the form of a partition extending from the front wall 19 to the back wall 18, and from the base 33 to the top of the casing. It is spaced from the side wall 16 a substantial distance to provide a compartment to house a fuel control 42 and a blower 43.

The fuel control 42 is connected to a source of fuel (not shown), and to the burner 31 by a conduit 44.

The blower is mounted on the baffle 40. The inlet of the blower casing registers with an opening in the baffle 40. The outlet of the blower is connected by a duct 45 to the grille 29.

When the heater is in operation air is drawn into the outer casing through the louvers 25. The

air is heated by the heat exchanger, rises by convection, and is discharged through louvers 24 into the room. If the blower 43 is operating, some of the air is drawn from the space to the left of baffle 40 and is discharged through the grille 29.

Air is also drawn through louvers 26 and opening 38 into the space between the base 33. Some of that air flows into the space around the burner through opening 33a and thence into the burner. The rest of the air flows out through openings 35, 36 and 37 into the passageways formed between the baffles 39, 40 and 41 and the respective walls of the outer casing. These baffles are heated by the heat exchanger and they in turn heat the air in the aforementioned passageways, setting up a circulation of air by gravity. The heated air is discharged into the top of the casing, from which it enters the room through louvers 24 and blower 43, and grille 29, if the blower is operating. The air flowing through the passageways keeps the adjoining side walls cool so that there is no danger from fire.

Air is also admitted to the space between side wall 16 and baffle 40 through louvers 28 and leaves through louvers 27. The oil control is thus kept cool, as well as the walls of this section of the casing.

If desired, an opening can be cut in the floor of the building directly beneath opening 20 in the floor plate of the heater to admit air to the space beneath the base of the heater. In case such an opening is provided, the louvers 26 can be closed off, or dispensed with.

From the foregoing it will be evident that the present invention provides a simple and economical heater that is particularly efficient, while at the same time it can be mounted in a wall with complete safety. Insulating of the side and back walls is performed by air, which also aids in heating the room. There is always some circulation of air by gravity, but if desired, the lower part of the room can be kept at a comfortable temperature by operating the blower 43.

The scope of the invention is indicated in the appended claims.

We claim:

1. A heater comprising an outer casing defined in part by upright walls, a heat exchanger in said casing, and a baffle in said casing interposed between said heat exchanger and one of said walls in spaced relation thereto, said baffle being substantially coextensive in area with said last named wall and forming therewith an air duct, the upright edges of said baffle being connected to certain walls of said outer casing, said air duct hav-

ing an air inlet opening adjacent its lower end and an air outlet opening adjacent its upper end, said baffle being provided with an opening therein adjacent said heat exchanger below the top thereof, and a blower having an inlet opening communicating with said opening in said baffle and an outlet opening communicating with an opening in one of said side walls of said casing.

2. A heater comprising an outer casing defined by four upright side walls and top and bottom walls, an upright baffle in said casing dividing the outer casing into two chambers, a heat exchanger in the first chamber, an air inlet opening in said baffle adjacent said heat exchanger,

10 16 a blower positioned in said second chamber and having an inlet opening communicating with said opening in said baffle, said blower also having an outlet opening communicating with an opening in one of the side walls of said casing and below the mid-portion of said side wall, said second chamber also having an air inlet opening in a side wall thereof adjacent the bottom wall and an air outlet opening in the side wall adjacent the top wall of said casing.

25 30 35 3. The combination as set forth in claim 2 wherein the first chamber is also provided with a baffle between the heat exchanger and the rear wall of the chamber and between the heat exchanger and the adjacent side wall of the outer casing, said baffles being spaced from the respective back and side walls of the outer casing and provided with air inlet openings adjacent their bottoms and air outlet openings adjacent their tops so that each baffle cooperates with its adjacent wall to provide an air duct.
